UNITED STATES PATENT OFFICE.

CLARENCE GRIFFITH STOLL, OF OAK PARK, ILLINOIS, ASSIGNOR TO WESTERN ELECTRIC COMPANY, INCORPORATED, OF NEW YORK, N. Y., A CORPORATION OF NEW YORK.

STRAND OR CORD WORKING MACHINE.

Application filed December 31, 1923. Serial No. 683,623.

To all whom it may concern:

Be it known that I, CLARENCE GRIFFITH STOLL, a citizen of the United States, residing at Oak Park, in the county of Cook and State of Illinois, have invented certain new and useful Improvements in Strand or Cord Working Machines, of which the following is a full, clear, concise, and exact description.

This invention relates to strand or cord working machines, and more particularly to a machine for binding a plurality of strand materials together.

An object of this invention is to provide a machine which will be efficient in operation and so compact in structure as to substantially increase the productive capacity of the floor space occupied by the machine.

A further object of this invention is to provide a machine so designed that the strand is drawn from the strand supplies and through the strand working devices and stored on the take-up devices with a minimum amount of bending thereof and with no deleterious friction or wear thereon.

In its preferred form the invention consists of a single unitary frame upon two opposite sides of which is mounted a pair of independently operable strand working devices. Associated with each strand working device is a pair of strand supplies arranged therebelow, side by side upon the same side of the frame and at an angle whereby the feed of the strand therefrom is focused on a guide positioned below the strand working devices. Mounted above and on a line intermediate the devices and each pair of strand supplies is a pair of concentric capstans of comparatively large size, one for each of the strand working devices, whereby the strand is subjected to a minimum amount of bending. The capstans operate in opposite directions to draw the pair of strands from each of the associated strand working devices and direct the worked strands to suitable guides and then to a storage device disposed below the strand working devices and upon that side of the machine upon which the strand supply for the opposite strand working device is positioned. Means, re-

sponsive to the tension on the strand material traveling from the capstans to the associated storage devices, is also provided for regulating the speed of the aforementioned storage devices and thereby maintaining a substantially constant tension on the strand between the said capstans and strand storage devices.

It will be apparent, however, that the features of this invention are readily applicable to other mechanisms and are not limited to their use with the apparatus disclosed.

Other objects and advantages of the invention will more fully appear from the following detailed description taken in connection with the accompanying drawings, in which—

Fig. 1 is a front view of the machine;

Fig. 2 is a view taken from the left-hand side of Fig. 1;

Fig. 3 is an enlarged vertical detail sectional view taken through the supply spool mechanism;

Fig. 4 is an enlarged vertical sectional view taken on the line 4—4 of Fig. 3 looking in the direction indicated by the arrows, and

Fig. 5 is an enlarged vertical sectional view of the capstan mechanism.

Referring now to the drawings in detail in which like reference numerals designate similar parts throughout the several views, 10 is a machine frame on which is mounted four complete binding units, two on each side of the frame. Each binding unit comprises four sub-units, a supply spool unit 11, a serving or binding unit 12, a capstan unit 13, and a take-up spool unit 14. These sub-units are mounted independently of each other in such a way that any one can be removed without disturbing the others.

Suitably located in the lower part of the frame 10 is a motor 15 which drives all four units through the medium of one main or common shaft and suitable intermediate gearing (not shown).

As shown in Fig. 2 the wires 16 are fed from the underside of the supply spools 17 and 18 to a guide 19 located in binding sub-

unit 12. The spools 17 and 18 are mounted at an angle with their heads adjacent, on a rotatable member 21, (Fig. 3) thereby enabling the strand materials to be withdrawn therefrom with a minimum amount of friction, the feeding angle of the strand materials being focused on the guide 19 (Figs. 1 and 2). Secured to a stud 22, which is suitably attached to the lower part 10 of the frame 10, is a stud 23 upon which the member 21 rotates. Located on top of the rotatable member 21 is a small cam lever 25 pivotally secured to a lock pin 26, which extends through the rotatable member 21. 15 As best shown in Fig. 4, the rotatable member 21 is locked against rotation through the engagement of the end of the lock pin 26 in an opening 27 in the stud 22. Formed around the lower part of the lock pin 26 is 20 a small collar 28 which fits snugly in an enlarged opening 29 in the rotatable member 21. Between the collar 28 and upper part of the opening 29 is a small compression spring 30, which upon the operation of cam lever 25 to lock the rotatable member 21, causes the lock pin 26 to be forced into its locked position. By unlocking the member 21 and rotating it and the spools attached thereto on the stud 22 the operator 25 is enabled to expeditiously unload and 30 reload the strand spool carrying member 21.

A chain 32 (Fig. 3), which is attached at one end to a lever 33, passes over a grooved pulley 34 which is mounted in a bracket 35 35 secured to the frame. The other end of the chain 32, which passes over pulley 34, is attached to a weight 36. A small length of chain 37 passes over the grooved pulley 34, being secured at one end to a handle 38, 40 whereas the other end is also secured to the weight 36. The weight 36 causes the chain 32 to be drawn taut, drawing up the lever 33, which in turn causes a lever shaft 41 to turn. The lever shaft 41, which is mounted 45 at one end in a support 42, in turn operates a series of levers, which causes a shoe 43 to be pressed against the material on the supply spool, thereby preventing the material from overrunning the spool and 50 also tending to maintain a constant tension on the strand being withdrawn. By drawing up the handle 38 and placing it in a bracket 44 mounted on the frame 10, the lever 33 drops of its own weight, causing 55 the shoe 43 to also drop.

The wires 16 to be bound together are drawn from the supply spools 17 and 18 through the guide 19, serving head 45, cop magazine brackets 46 and cops 47 by a 60 power driven capstan 48 located in the capstan unit 13.

As shown in Fig. 5, capstan unit 13 consists of two concentric capstans 48 and 49 of the same diameter, having interlocking flanges and rotatable in opposite directions.

The capstan bearing housing 50 in which the capstan mechanism is located is secured to the frame 10. Keyed to the end of a vertical shaft 51 is a bevel gear 52 which is meshed with a bevel gear 53. The bevel gear 53 is secured to a capstan shaft sleeve 54 by a key 55. Keyed to the vertical shaft 56 is a bevel gear 57 which is meshed with a bevel gear 58. The bevel gear 58 is secured to a capstan shaft 59 by a key 60. 70 Separating the two bevel gears 58 and 53 is a shoulder 61 on the capstan shaft 59 and two thrust collars 62 and 63. The capstan shaft 59 revolves in the capstan shaft sleeve 54 and bearing 64, while the capstan shaft 59 and in the bearing 65. 75

Located on the capstan shaft sleeve 54 are two thrust washers 68 and 69. A thrust washer 70 on the capstan shaft 59 separates 80 the hubs of the capstans 49 and 48. The capstan 49 is secured to the capstan shaft sleeve 54 by a key 71 and the capstan 48 is secured to the capstan shaft 59 by a key 72. Two lock nuts 73 and 74 on the end of 85 the capstan shaft 59 retain the two capstans 48 and 49 in their respective positions. Located throughout the capstan bearing housing 50 are oil feeds, such as 75, 76 and 77. A thrust washer 78 fits around the capstan 90 shaft 59 and between the housing 50 and the bevel gear 58. The vertical shafts 51 and 56 revolve in the bushings 66 and 67 and the bearings 79 and 80.

Suitably located in each unit is a tension 100 arm assembly 81 which is responsive to the tension on the strand material traveling from the capstan sub-unit 13 to the take-up spool sub-unit 14 and adapted to thereby regulate the speed of the said take-up spool 105 sub-unit 14, thus preventing any undue tension upon the strand.

A tension mechanism of this type is more fully disclosed in detail in patent to F. S. Kochendorfer et al., No. 1,520,718, dated December 30, 1924, to which reference may be had for a full description of the operation thereof.

After the bound wires 16 leave the capstan 48 they pass over the tension arm assembly 81 to a guide 85 which directs the wires to a power driven take-up reel 82 in the take-up unit 14. A capstan release lever 83, as best shown in Figs. 1 and 2, is used to control a spiral jaw clutch (not shown) 115 located around the upper part of the vertical shaft 56 and in the cover 84, the function of this clutch being to disconnect the vertical shaft 56 from a motor driven shaft 120 (not shown). Whenever the speed of the take-up spool unit 14 becomes so great that the tension arm assembly 81 is unable to regulate it, or when the tension arm assembly 81 fails to operate, this spiral jaw clutch operates to permit the capstan 48 125 130

to turn faster than the above mentioned power driven shaft without having to turn this shaft and the motor with it. A lever 86 operates a disc clutch (not shown) associated with the driving mechanism of one complete unit. By operating this lever the mechanism of that particular unit can be stopped without interfering with the other three units.

10 The machine above described, having a pair of independently operable strand working devices upon two opposite sides thereof with a pair of comparatively large diameter capstans for each pair of devices arranged concentrically thereabove for drawing the worked strand therethrough provides a machine which has great productive capacity for the floor space occupied thereby. The concentric mounting of the capstans reduces the floor space occupied by the machine compared to a similar machine having each capstan mounted upon a separate shaft where the capstans are of the same diameter in both instances. Also due to the 20 comparatively large diameter capstans and the angular mounting of the strand supplies below the strand working devices for focusing the strands upon the guide positioned below the strand working devices, the strand 25 30 is drawn through the strand working devices and around the capstans and stored on the take-up reel with a minimum bending thereof, and with no deleterious friction or wear thereon.

35 What is claimed is:

1. In a strand working apparatus, two spools of strand material, a mechanism for binding said strand material together, said mechanism having a serving device and 40 a guide associated therewith, a rotatable member for rotatably supporting each of said spools at an angle and with their heads adjacent whereby the feed of the strand material therefrom is focused on said guide, and 45 means for locking said member against rotation.

2. In a strand working apparatus, a plurality of supply devices, a plurality of strand working devices, a plurality of capstans for withdrawing strand material from 50 said supply devices and subjecting them to said strand working devices, said capstans concentric and rotatable in opposite directions, and a plurality of strand storage devices for receiving the strand material from said capstans.

3. In a strand working apparatus, a plurality of supply devices, a plurality of strand working devices, a plurality of capstans for withdrawing strand material from 60 said supply devices and subjecting it to said strand working devices, said capstans concentric and rotatable in opposite directions, a plurality of strand storage devices 65 for receiving the strand from said capstans,

and means responsive to the tension on said strand material for controlling the speed of said storage devices.

4. In a strand working apparatus, a plurality of supply devices, a plurality of strand working devices, a plurality of capstans for withdrawing strand material from 70 said supply devices and subjecting it to said strand working devices, said capstans concentric, of the same diameter and rotatable in opposite directions, and a plurality of strand storage devices for receiving the strand material from said capstans.

5. In a strand working apparatus, a plurality of supplies of strand material, a pair 80 of strand working devices, each comprising a rotatable member and a guide associated therewith, a pair of concentric capstans of the same diameter, each of said guides disposed in substantially the same plane with the peripheries of said capstans and at opposite sides thereof, and a plurality of strand storage devices for receiving the strand material from said capstans.

6. In a strand working apparatus, a pair 90 of strand working devices, each comprising a rotatable member and a guide associated therewith, a pair of concentric capstans of the same diameter, each of said guides disposed in substantially the same plane with the peripheries of said capstans and at opposite sides thereof, a pair of spools containing strand material associated with each of said strand working devices, the spools of each pair set at an angle so that the angles 95 of feed of the strand material therefrom are focused on their associated guide.

7. In a strand working apparatus, a plurality of supplies of strand material, a pair 105 of strand working devices, each comprising a rotatable member and a guide associated therewith, a pair of concentric capstans of the same diameter, said capstans rotatable in opposite directions, each of said guides disposed in substantially the same plane 110 with the peripheries of said capstans and at opposite sides thereof, and a plurality of strand storage devices for receiving the strand material from said capstans.

8. In a strand working apparatus, a pair 115 of strand working devices, a strand supply for each of said devices, means arranged concentrically and operable in opposite directions for drawing the worked strand from each of said devices, and a strand storage device associated with each of said drawing means and working devices for receiving the worked strand therefrom, said strand storage devices each disposed upon that side of the apparatus upon which the strand supply for the opposite strand working device is located.

9. In a strand working apparatus, a pair 125 of strand working devices, a plurality of strand supplies for each of said devices 130

arranged therebelow, a pair of concentric capstans disposed above and intermediate said devices and adapted to operate in opposite directions for drawing the worked strand from said devices, and a strand storage device associated with each of said capstans and working devices for receiving the worked strand therefrom, said strand stor-

age devices each disposed upon that side of the apparatus upon which the strand supply 10 for the opposite strand working device is located.

In witness whereof, I hereunto subscribe my name this 19th day of December, A. D. 1923.

CLARENCE GRIFFITH STOLL.
